(57) **CLAIM**

The ornamental design for a light emitting device, as shown and described.

DESCRIPTION

FIG. 1 is a front, left perspective view of a light emitting device showing our new design;

FIG. 2 is a front elevational view of the light emitting device;

FIG. 3 is a rear elevational view of the light emitting device;

FIG. 4 is a left side view of the light emitting device;

FIG. 5 is a right side view of the light emitting device;

FIG. 6 is a top plan view of the light emitting device; and,

FIG. 7 is a bottom plan view of the light emitting device.
